(57) **CLAIM**

The ornamental design for range hood, as shown and described.

DESCRIPTION

FIG. 1 is a perspective view from the front, right side, and top of a range hood showing our new design.

FIG. 2 is a front elevational view thereof.

FIG. 3 is a right side elevational view thereof, the left side elevational view being a mirror image thereof; and,

FIG. 4 is a bottom plan view thereof.

The sides not shown are disclaimed.
